SPUTUM COLLECTING DEVICE

Gerald M. Arsenault, Bayside, and Melvin P. Ehrlich, Roslyn Estates, N.Y., assignors to Nuclear Research Associates, Inc., New Hyde Park, N.Y., a corporation of Delaware

Filed Feb. 21, 1968, Ser. No. 10,668

Term of patent 14 years

U.S. Cl. D16—1

Int. Cl. D24—05

FIG. 1.

FIG. 2.

FIG. 3.

FIG. 4.

FIG. 1 is a side elevation of a sputum collecting device, showing our new design;

FIG. 2 is a view similar to FIG. 1 with the device being rotated 90°;

FIG. 3 is a bottom plan view thereof; and

FIG. 4 is a top plan view.

We claim:

The ornamental design for a sputum collecting device, as shown.
